United States Patent Office

Des. 192,606
Patented Apr. 17, 1962

192,606

DISH

Leo F. Wildgen, Minneapolis, Minn., assignor to Arthur Salm Inc., Chicago, Ill., a corporation of Illinois

Filed Sept. 5, 1961, Ser. No. 66,610

Term of patent 14 years

Claims priority, application Germany Mar. 7, 1961

(Cl. D44—15)

Fig 1

I claim:

The ornamental design for a dish, substantially as shown and described.
